(**) Term: **14 Years**

The ornamental design for an egg-shaped ribbon dispenser carton, as shown and described.

DESCRIPTION

FIG. 1 is a perspective view of a first embodiment of the egg-shaped ribbon dispenser carton showing our new invention;

FIG. 2 is a front elevation view thereof;

FIG. 3 is a rear elevation view thereof;

FIG. 4 is a side elevation view thereof;

FIG. 5 is another side elevation view thereof;

FIG. 6 is a top view thereof;

FIG. 7 is a bottom view thereof;

FIG. 8 is a perspective view thereof;

FIG. 9 is a front view thereof;

FIG. 10 is a back view thereof;

FIG. 11 is a side view thereof;

FIG. 12 is a side view thereof;

FIG. 13 is a top view thereof; and,

FIG. 14 is a bottom view thereof.

The broken line showing of the environment is for illustrative purposes only and forms no part of the claimed design.
